LAMP RECEPTACLE

Filed Oct. 13, 1927

FIG. 6.

INVENTOR.
Raymond H. Alley :
BY Parsons & Bodell
ATTORNEY.

ATTORNEYS,

UNITED STATES PATENT OFFICE

RAYMOND H. OLLEY, OF SYRACUSE, NEW YORK, ASSIGNOR TO CROUSE-HINDS COMPANY, OF SYRACUSE, NEW YORK, A CORPORATION OF NEW YORK

LAMP RECEPTACLE

Application filed October 13, 1927. Serial No. 225,910.

This invention relates to lamp sockets and has for its object a lamp socket in which the outer sleeve terminal and the central lamp contact and wire terminals are a self contained unit and mountable as a unit on a lamp base, which lamp socket is particularly simple and economical in construction and highly efficient in use.

The invention consists in the novel features and in the combinations and constructions hereinafter set forth and claimed.

In describing this invention, reference is had to the accompanying drawing in which like characters designate corresponding parts in all the views.

Figures 1 and 2 are respectively, opposite side elevations of this lamp socket assembled on its base.

Figure 3 is a plan view of parts seen in Figures 1 and 2.

Figure 4 is a side elevation of the detached self contained lamp socket unit.

Figure 5 is a sectional view on line 5—5, Figure 4.

Figure 6 is an elevation partly broken away of the lamp base.

This lamp socket comprises generally an outer sleeve terminal and a central lamp contact supported entirely by and within the sleeve terminal whereby the sleeve terminal and the central lamp contact with their wire terminals are assembled as a unit and mountable as a unit on a base, the sleeve terminal having means for securing the unit to the base.

1 designates the sleeve terminal which is formed with internal threads 2, the sleeve terminal being open at both ends and having an opening 3 in its side for the wire terminal of the central lamp contact to be presently described.

4 designates the central lamp contact which is carried by an insulating support secured within the inner end of the sleeve terminal 1 and which has a wire terminal 5 extending through the opening 3 to the outside of the sleeve terminal 1 where it is provided with a binding screw 6.

50 The support for the central contact includes an insulating block as a disk 7 per-

manently secured in the sleeve terminal 1. It is here shown as secured therein by a second insulating disk 8, the two disks thrusting against internal oppositely facing shoulders 9 and 10 within the sleeve terminal, and the two disks being clamped against the shoulders by a pin 11 extending axially through the disks and secured as by riveting on the outer faces of the disks. A spacing sleeve 12 is interposed between the disks 8 and surrounds the pin 11. The shoulders 9, 10 are preferably annular.

The central contact 4 extends under the wire terminal 5 and the upper head 13 of the rivet overlies the wire terminal 5. The central contact is here shown as in the form of a V shaped clip having a hole 14 at or near its angle through which the wire terminal 5 extends to overlie one arm of the clip.

The sleeve terminal is usually formed heavier than the usual screw threaded shell and is provided with a binding screw or wire terminal 15 on the outside thereof, this binding screw 15 being located diametrically opposite the binding screw 6.

The outer sleeve terminal 1 and the central lamp contact with its support thus constitute a self contained unit and this unit is mountable on an insulating base 16 provided with upright segmental arc shaped walls 17 for centering the lamp socket with the wire terminals in line with wire holes 18. The base is also provided with suitable fastening means as screws 20 for attaching it to a fixture.

In order that the rigid screw threaded sleeve terminal will firmly hold the threaded lamp plug or base, it is provided with distorted threads and the threads are distorted by forming a transverse slot 19 in the sleeve terminal, which slot opens through the internal threaded face of the terminal and the slot contracted or the walls pressed toward each other to close or partly close the slot.

The means for securing the lamp socket to the base are here shown as laterally extending lugs 21 provided on the sleeve terminal 1 and overlying the upper ends of the walls 16 or embedded in recesses therein and

a screw 22 extending through the base and threading into the lugs.

This lamp socket or receptacle is particularly adapted for situations where sturdy lamp sockets are desired as trains, cabs of locomotives and any other situation where the receptacles are required to perform heavy duty.

What I claim is:

10 1. A lamp socket comprising an outer sleeve terminal having internal shoulders facing in opposite directions, insulating disks within the sleeve terminal and abutting against said shoulders, means for securing the disks together and holding them against the shoulders and a central lamp contact carried by the innermost disk.

20 2. A lamp socket comprising an outer sleeve terminal having internal shoulders facing in opposite directions, insulating disks within the sleeve terminal and abutting against said shoulders, means for holding the disks against the shoulders and a central lamp contact carried by the innermost disk, the sleeve terminal having a wire terminal carried thereby on the bottom portion thereof between said shoulders, and the central lamp contact having a wire terminal projecting laterally therefrom through the

30 sleeve terminal.

In testimony whereof, I have hereunto signed my name, at Syracuse, in the county of Onondaga, and in the State of New York, this 10th day of October, 1927.

35 RAYMOND H. OLLEY.
